(57) **CLAIM**

The ornamental design for an anvil for surgical stapler, as shown and described.

DESCRIPTION

1.1: Front view of an anvil for surgical stapler according to a first design;

1.2: Back view of the anvil for surgical stapler of 1.1;

1.3: Left view of the anvil for surgical stapler of 1.1;

1.4: Right view of the anvil for surgical stapler of 1.1;

1.5: Top view of the anvil for surgical stapler of 1.1;

1.6: Bottom view of the anvil for surgical stapler of 1.1;

2.1: Front view of an anvil for surgical stapler according to a second design;

2.2: Back view of the anvil for surgical stapler of 2.1;

2.3: Left view of the anvil for surgical stapler of 2.1;

2.4: Right view of the anvil for surgical stapler of 2.1;

2.5: Top view of the anvil for surgical stapler of 2.1;

2.6: Bottom view of the anvil for surgical stapler of 2.1;

2.7: Perspective view of the anvil for surgical stapler of 2.1; and

2.8: View showing anvil for surgical stapler of 2.1 in use.

The broken lines shown in the figures depict portions of the anvil for surgical stapler that form no part of the claimed design.

1 Claim, 14 Drawing Sheets
